CLAIM

We claim the ornamental design for a wireless charging receiver, as shown and described.

DESCRIPTION

FIG. 1 is a top rear perspective view of a wireless charging receiver showing our new design;

FIG. 2 is a top front perspective view of a wireless charging receiver showing our new design;

FIG. 3 is a top view of the wireless charging receiver of FIG. 1;

FIG. 4 is a bottom view of the wireless charging receiver of FIG. 1;

FIG. 5 is a left side view of the wireless charging receiver of FIG. 1;

(Continued)

FIG. 6 is a right side view of the wireless charging receiver of FIG. 1;

FIG. 7 is a front view of the wireless charging receiver of FIG. 1; and,

FIG. 8 is a rear view of the wireless charging receiver of FIG. 1.

The broken lines in the figures represent portions of the article which form no part of the claim.

1 Claim, 8 Drawing Sheets
